(57) **CLAIM**

The ornamental design for a streamlined pressure gauge, as shown and described.

DESCRIPTION

FIG. 1 is a top view of an ornamental design for a pressure gauge; and,

FIG. 2 is a side view of the device of FIG. 1, wherein the opposite side is a mirror image thereof.

The broken line showing of the pressure gauge of the figures is for illustrative purposes only and forms no part of the claimed design. Likewise, shading shown in the figures is for illustrative purposes only and forms no part of the claimed design.
